PATTERN SPRINKLER

Royal N. Riblet, Spokane, Wash.

Application June 28, 1950, Serial No. 170,909

5 Claims. (CL. 299—18)

1

The present invention relates to improvements in pattern sprinklers.

It is the principal purpose of my invention to provide a sprinkling device which can be made to distribute water evenly over an area that is normally circular, such as a square area, from a rotating sprinkler head, which sprinkler being of such construction that it delivers water in proportion to the area to be covered.

It is of course, old in the art to provide sprinklers which will cover a square area. Such devices however, have not come into common use despite the obvious advantages that would appear to float from their use. In irrigating large tracts of land by means of sprinklers, one of the greatest difficulties arises from the fact that rotating sprinklers covering circular areas require overlapping of the sprinkled areas to obtain complete coverage. The overlapped areas receive too much water if the other areas receive enough. If the areas can be rectangular or preferably square with uniform water distribution, the overlapping is unnecessary. Fewer sprinklers are needed and the water coverage is more uniform.

In sprinkling a non-circular area, it is obvious that the portions of the area extending farthest from the sprinkling center must have a greater volume of water if a rotating sprinkler is used and it rotates at a uniform rate of speed. According to my invention I provide a simple, efficient rotating sprinkler with means for causing the throw from the sprinkler head to vary between minimum and maximum distances and vary the amount of water delivered so that the greater area covered with the greater distance of throw receives a proportionately greater amount of water.

More particularly it is a purpose of my invention to provide a rotating type of sprinkler with a novel driving mechanism by which the spray nozzle is rotated at a substantially constant rate of speed and the spray nozzle is elevated and lowered according to a cam and roller pattern wherein the flow of water to the spray nozzle is increased and decreased as the nozzle is raised and lowered, the flow to the driving mechanism being substantially constant.

The nature and advantages of my invention will appear more fully from the following description and the accompanying drawings. It should be understood however, that the drawings and description are illustrative only and are not intended to limit the invention except as it is limited by the claims.

2

In the drawings:

Figure 1 is a view in side elevation of my improved sprinkler with the housing therefor shown in section;

Figure 2 is a plan view of the sprinkler with the housing broken away;

Figure 3 is a sectional view taken on the line 3—3 of Figure 2;

Figure 4 is a fragmentary sectional view taken on the line 4—4 of Figure 3;

Figure 5 is a fragmentary sectional view taken on the line 5—5 of Figure 2;

Figure 6 is a fragmentary plan section illustrating a modified construction;

Figure 7 is a section view on the line 7—7 of Figure 6;

Figure 8 is a view in side elevation of a preferred form of the nozzle; and

Figure 9 is an enlarged end view of the nozzle showing the construction of the outlet end thereof.

Referring now in particular to Figures 1, 2 and 3, my improved sprinkler is adapted to mount upon a suitable support 10 having an upright standard 11 which may have a suitable inlet, not shown, for the supply of water. The standard 11 has a nipple 12 which is threaded to receive a hollow supporting member 13 for the sprinkler mechanism. The support member 13 has a sleeve 14 rotatably journaled therein. The sleeve 14 carries the rotating parts of the sprinkler and control means for the flow of water to the sprinkler nozzle. The sleeve 14 has an enlarged head 15 which bears against the lower end of the supporting member 13. The upper end of the sleeve 14 is threaded to receive a valve body 16. When the sprinkler is at rest the valve body 16 rests upon the upper end of the member 13, however, when water pressure is applied, the pressure will tend to raise the valve body 16 and the sleeve 14 to cause the head 15 to bear against the lower end of the member 13. With a good bearing fit between the member 13 and the sleeve 14, I find no difficulty with leakage of water past the long bearing surface provided by these two members.

In order to rotate the valve body 16, I provide a water wheel 17 by mounting a bracket 18 on the upper end of the valve body and mounting a worm shaft 19 on the bracket 18. Two bearing blocks 20 and 21 support the shaft 19. A worm 22 is keyed to the shaft 19 and is positioned between two collars 23 and 24 which prevent end-wise movement of the worm. The water wheel 17 is on the end of the shaft 19 and is supplied

3

with water through the sleeve 14 and through the valve body 16 by a pipe elbow 25, a short length of pipe 26 and a nozzle 27.

The worm 22 drives a worm gear 23 which is fixed on an upright shaft 29 that is journaled in the bracket 18. The shaft 29 extends down through a guide stem 30 and is provided at its lower end with a pinion 31 that meshes with a large gear 32. The gear 32 has a hub 33 that is fixed to the member 13 by a set screw 34. The gear 32, being fixed on the member 13 remains stationary. The pinion 31 travels around the gear 32 causing rotation of the bracket 18, the parts carried thereby, the valve body 16 and the parts carried thereby. The worm 22, the worm gear 28, the pinion 31 and the gear 32 provide means for causing a slow rotation of the valve body 16 for a relatively high speed rotation of the water wheel 17. Very little force is necessary to drive the wheel 17. The sprinkler, therefore, can operate on a low water pressure.

The valve body 16 has a valve 36 therein provided with a port 37 and an end outlet 38. The valve 36 is journaled for rotation in the valve body 16. At one end a washer 39 and a nut 40 are provided on the valve 36. At the other end of the valve 16, a cam follower mounting bracket 41 is fixed on the valve by a set screw 42. A bushing 43 is interposed between the valve body 16 and the bracket 41. A spray nozzle 44 is connected to the outlet opening 37 by an elbow 45 which is threaded into the outlet opening 38. A lock nut 46 on the elbow 45 prevents the elbow from working loose.

The bracket 41 carries a cam follower roller 47 that rides on the surface of an annular cam 48. The cam 48 is mounted on the gear 32. Since the roller 47 is secured on the bracket 41, the bracket 41 will rock the valve 36 as the roller rises and falls in its travel along the top edge of the cam 48. The spray nozzle 44 and the bracket 41 are adjusted on the valve 36 in the proper relation to the port 37 of the valve to have the nozzle 44 at its maximum elevation and the valve port 37 open to the greatest extent when the roller 47 is on the lowest part of the cam 48. The nozzle 44 discharges in such a direction that the back pressure serves to hold the roller 47 on the cam 48. As the roller 47 is raised in traveling over the cam 48, the valve 36 is turned in a direction to decrease the port area by covering part of the port 37 by the valve body wall at 16a. The nozzle is lowered at the same time.

The cam 48, as shown, is cut to cause the nozzle to direct spray over a square area. The spray is directed to the corners of the square when the roller is at the lowest spots on the cam. The greatest water flow also occurs at these positions of the roller because the port 37 is most nearly open. Obviously by changing the surface of the cam 48 a different shaped pattern of spraying will be produced.

In order to protect the mechanism of the sprinkler I provide a housing 50. The housing is secured on the valve body 16 by a stem 49. The stem 49 is threaded into the upper end of the valve body. The housing is clamped to the stem by two nuts 51 and 52 and a washer 53. The bottom of the housing is closed by a separable plate 54 that has a central guide ring 55 around the pipe 13. The housing fits over the flange 56 of the plate and may be secured thereto by screws. Openings are provided at 57 and 58 for the spray from the nozzles 44 and 27. The plate 54 has drain openings 59 therein.

4

The nozzle 44 preferably has its outlet shaped as indicated in Figure 9. This forms a large main aperture 60 and a depending slot 61 gives a fan like spray that distributes the water quite evenly over the distance the stream reaches. In some instances it is advantageous to provide two branches 44a and 44b of the nozzle as indicated in Figure 8. The branches are set at different angles to the supply pipe 44c, so the upper branch sprays the outer portion and the lower nozzle sprays the inner portion of the area covered.

The modification illustrated in Figures 6 and 7 operates in the same fashion as the preferred form. The only difference is that the cam 48' is flat topped but square and the roller 47' is cone-shaped so that the radial distance from the center of rotation varies about the cam and the cone roller 47' causes the bracket 41' to move up and down.

The sprinkler mechanism described herein is highly advantageous in sprinkler irrigation systems where portable pipe systems are employed to sprinkle areas of large extent. These systems usually employ a series of sprinklers on a long supply pipe that extends across the field. The pipe is moved transversely of its length after an area has been sprinkled. With the sprinklers that cover a circular area, the sprinkler heads must be spaced to overlap the circles enough to equal the difference between the area diameter and the side dimension of the largest square that can be formed inside the circular area. Otherwise patches are left without any water. The overlapped portions get too much water.

With my improved sprinkler the sprinkler heads can be placed far apart because the amount of overlapping is not necessary. The area covered crosswise of the main supply pipe is also greater because there is no necessity of overlapping in this direction. In addition the device has the advantage of avoiding over watering any particular section.

I am of course, aware that square sprinklers have been proposed and devised purporting to sprinkle square areas and have been patented. In spite of the apparent obvious advantages of such devices, they have not come in general use where a great amount of irrigation is carried on by sprinkling. The mechanism of my improved sprinkler has operated successfully in field tests. The method of driving the sprinkler insures a uniform rotational speed so that the variation in water flow by opening and closing the valve to the sprinkler head is quite effective in obtaining uniformity of water distribution over the area. It will be appreciated that by having the water flow to the driving water wheel directly in communication with the supply to the valve and to the sprinkler, the opening of the valve, when the sprinkler is at its greatest elevation, operates to retard the speed of rotation by lowering the pressure in the supply line. In this way it is possible to obtain a sufficient supply of water into the corners of the square to wet the ground as much as it is wet along the sides of the square where the valve is partially closed and the pressure in the supply line is naturally higher.

It is believed that the nature and advantages of my invention will be clear from the foregoing description. Having thus described my invention, I claim:

1. A sprinkler comprising a hollow supporting member, a sleeve journaled therein, a large gear fixed on the supporting member, a valve body fixed on the sleeve, a bracket on the valve body,

a water wheel, a worm, a shaft for the wheel and worm rotatably mounted on the bracket, a worm gear meshing with the worm, a shaft for the worm gear rotatably mounted by said bracket, a pinion on said last named shaft in mesh with the large gear on the supporting member, a nozzle positioned to direct water against the water wheel to rotate it, pipe means connecting the nozzle to the valve body, a tubular valve rotatably mounted in said body above the connection for said nozzle, said valve having an inlet port in its wall in position to admit more or less water from the valve body to the interior of the valve as the valve is turned on its axis, said valve having an end outlet, a spray nozzle fixed to the valve at said end outlet and extending upwardly and then laterally with respect to the axis of rotation of the valve, a cam follower bracket fixed to said valve, an annular cam on said large gear, and a cam follower roller on the bracket riding on the cam to move the bracket up and down as the roller is raised and lowered in rolling over said cam.

2. In a sprinkler, a hollow upright supporting member for connection to a source of water under pressure, a valve body rotatably mounted by the supporting member to rotate on a vertical axis and having its inlet open to the interior of said member, a tubular valve extending through the body on a horizontal axis and rotatably mounted in the body, said valve having an inlet port in the side wall thereof opening more or less to the interior of the valve body as the valve is rotated on its axis, said valve having an end outlet, a spray nozzle carried by said valve and connected to said outlet, said nozzle being directed in a plane transverse to the axis of the valve, means to rotate said valve body on the member, and means, operable as the valve body rotates, to rock the valve on its axis.

3. A sprinkler comprising a hollow upright supporting member, a large gear fixed to the top thereof, a sleeve rotatably mounted in the member and open at both ends so that water under pressure may flow up through said member and sleeve, a valve body carried by said sleeve, a water wheel carried by said body, a nozzle for directing water to the wheel in communication with the interior of said body, means operably connecting the water wheel to said large gear to effect rotation of the valve body and sleeve, a housing carried by the valve body and enclosing the valve body, the gearing and the large gear, a tubular valve rotatable in said body on a horizontal axis and having a port open to the body and an end outlet, a spray nozzle carried by the valve and offset therefrom and communicating with the

end outlet, said housing having an aperture for the spray nozzle to discharge water through, a cam on the large gear, and an arm on the valve having a cam follower riding on the cam to rock the valve in said body as the body rotates.

4. A sprinkler for sprinkling non-circular areas comprising a hollow upright supporting member, a large gear fixed to the top thereof, a valve body rotatably supported by the member to rotate about an upright axis, a water wheel carried by said valve body, a nozzle for directing water to the wheel in communication with the interior of said body, means operably connecting the water wheel to said large gear to effect rotation of the valve body and sleeve, a housing carried by the valve body and enclosing the valve body, the gearing and the large gear, a tubular valve rotatable in said body on a horizontal axis and having a port open to the body and an end outlet, a spray nozzle carried by the valve and offset therefrom and communicating with the end outlet, said housing having an aperture for the spray nozzle to discharge water through, a cam on the large gear, and an arm on the valve having a cam follower riding on the cam to rock the valve in said body as the body rotates.

5. A sprinkler for sprinkling non-circular areas comprising a hollow upright supporting member, a large gear fixed to the top thereof, a valve body rotatably supported by the member to rotate about an upright axis, a water wheel carried by said valve body, a nozzle for directing water to the wheel in communication with the interior of said body, means operably connecting the water wheel to said large gear to effect rotation of the valve body and sleeve, a housing carried by the valve body and enclosing the valve body, the gearing and the large gear, a tubular valve rotatable in said body on a horizontal axis and having a port open to the body and an end outlet, a spray nozzle carried by the valve and offset therefrom and communicating with the end outlet, said housing having an aperture for the spray nozzle to discharge water through, a square cam on the large gear, and an arm on the valve having a cone shaped cam follower riding on the cam to rock the valve in said body as the body rotates.
